UNITED STATES PATENT OFFICE.

GEORGE MAURICE WRIGHT, OF LONDON, ENGLAND, ASSIGNOR, BY MESNE ASSIGNMENTS, TO RADIO CORPORATION OF AMERICA, A CORPORATION OF DELAWARE.

THERMIONIC DEVICE.

1,394,601.

Specification of Letters Patent. Patented Oct. 25, 1921.

Application filed May 1, 1918. Serial No. 231,872.

To all whom it may concern:

Be it known that I, GEORGE MAURICE WRIGHT, a subject of the King of Great Britain, residing at Marconi House, Strand, 5 London, W. C. 2, England, have invented new and useful Thermionic Devices, of which the following is a specification.

This invention relates to the employment of thermionic devices or relays of the type 10 comprising a filament (acting as a cathode), a grid and an anode, for the purpose of magnifying electric currents or differences of potential.

In some cases it has been found impossible 15 to produce with one such relay sufficient magnification, and in consequence two or more relays have been used. Such a succession of relays, however, involves a great complexity of circuits, and it is difficult to control 20 the reactions in the whole apparatus.

The object of this invention is so to arrange a succession of these thermionic relays that the strength of atmospheric disturbances is reduced while at the same time any 25 desired magnification can be obtained with great simplicity of circuits.

In the accompanying drawing, I have illustrated one embodiment of my invention.

According to this invention to the anode 30 of a thermionic relay is connected one end of a high resistance, preferably of the order of the resistance of the relay itself, and the other end thereof is connected to the positive pole of a high tension battery the negative of which is connected to the filament. The junction 35 between the anode and the resistance is connected to the grid of a second relay the filament of which is connected to a point in the battery which is at the same potential as, or, alternatively at any desired small potential 40 difference from, the said junction. The anode and filament of the said second relay are similarly connected through a high resistance and battery. The junction between the anode of this second relay and its resistance 45 and a point in the battery may be similarly connected to the grid and filament respectively of the next relay, and so on.

When therefore the grid and filament of 50 the first relay are connected in an initial circuit so that the potential of the grid with reference to the filament is varied in any way, a corresponding variation is caused in the resistance of the space between the anode 55 and the filament which causes a magnified

variation in the difference of potential between the junction and the point in the battery connected to the second filament. This difference of potential is again magnified by the second relay, and so on. 60

The figure shows a thermionic device in accordance with this invention, f being the filament, a the anode and g the grid which is interposed between them, while connected to the anode is a high resistance r . H is a. 65 high voltage battery having its negative terminal connected to the filament battery b and its positive terminal connected to the resistance r . For the purpose of maintaining the correct potential between the grid and 70 the filament, the oscillatory circuit $L C$ is connected to the grid g and the potentiometer p .

When the relay is working a current flows around the anode circuit $a r H f$ and there 75 will be a certain drop of potential along the resistance r and a certain drop from anode to filament of the relay making it possible to find a point m on the battery H such that there will be no potential difference between 80 m and the point n , or it is possible by selection of m to make this potential difference any required value within limits.

Now if the potential of the grid g with reference to the filament f be varied, the 85 current in the anode circuit $a r H f$ will vary accordingly, which is equivalent to a variation of internal resistance, and this varying current will cause corresponding variations in the potential difference between 90 m and n . This latter variation is applied to the grid and filament of a second relay similarly connected and the series may be continued as far as desired. The figure shows a succession of three relays in which 95 the magnified variations of potential applied to the grid of the last relay cause a magnified oscillatory current to flow in the circuit $L^2 C^2$.

While at the same time magnifying weak 100 signals the apparatus also has the property of reducing the strength of atmospheric disturbances. Normally the relays are operated in such a condition that the current in their respective grid circuits is negligible, but if the variations of potential of n with 105 regard to m are so large that a current is caused to flow from n to m across the grid-filament space of the second relay, then a limiting action takes place. Immediately 110

2

this current begins to flow the potential difference between n and m will be reduced thereby. Since each relay will pass current only in the direction from grid to filament, 5 the second of the series will reduce impulses above a certain strength such as to tend to make n positive with regard to m . This limiting action will not occur when the impulse is such as to make n negative with regard to m and when this is the case n^1 will 10 become positive to m^1 and the current from n^1 to m^1 across the grid-filament space of the third valve will effect the reduction of potential difference between n^1 and m^1 . 15 Accordingly with two valves connected as described in this specification both positive and negative impulses applied to the grid of the first relay will be magnified in a lesser degree when these impulses are large 20 than when they are small.

Such a succession of relays may be adapted with suitable modifications for strengthening signals received by ordinary line or cable telegraphy as well as by wireless telegraphy. The drawing shows it as especially 25 applicable for use in the reception of wireless telegraph signals. The initial circuit referred to is an oscillatory circuit coupled to the aerial and the potential difference across 30 the junction and the corresponding point in the battery of the last relay acts upon a tuned circuit and produces oscillations therein which may be detected in any of the well known ways.

35 What I claim is:—

1. The combination of a thermionic relay having a cathode, grid and anode, a resistance connected to the anode thereof, a battery connected to the resistance and to the 40 cathode of the relay, and a second thermionic relay having a cathode, grid and anode having its grid connected to the anode of the first and its cathode to a point in the battery between its terminals.

45 2. The combination of a thermionic relay having a cathode, grid and anode, a resistance connected to the anode thereof, a battery connected to the resistance and to the

cathode of the relay, and a second thermionic relay having a cathode, grid and anode having its grid connected to the junction between the anode of the first relay and the resistance and its cathode to a point in the battery which is at the same potential as the said junction. 50

3. The combination of a thermionic relay having a cathode, grid and anode, a resistance connected to the anode thereof, a battery connected to the resistance and to the cathode of the relay, a second thermionic 60 relay having a cathode, grid and anode having its grid connected to the anode of the first and its cathode to a point in the battery between its terminals, a second resistance connected to the anode of the second 65 relay and a second battery connected to the second resistance and to the cathode of the second relay.

4. The combination of successive thermionic relays, each having a cathode, grid 70 and anode, and each relay except the last having a resistance connected to its anode and a battery connected to the resistance and to its cathode, and each relay after the first having its grid connected to the anode 75 of the preceding relay and having its cathode connected to a point between the terminals of the battery of the anode circuit of the preceding relay.

5. The combination of successive thermionic relays, each having a cathode, grid and anode, and each relay except the last having a resistance connected to its anode and a battery connected to the resistance and to its cathode, and each relay after the 80 first having its grid connected to the junction between the anode of the preceding relay and the resistance and having its cathode connected to a point in the battery of the anode circuit of the preceding relay 85 90 which is at substantially the same potential as the said junction.

In testimony that I claim the foregoing as my invention, I have signed my name this 10th day of April, 1918.

GEORGE MAURICE WRIGHT.
